Primary Examiner — Jonathan J Han(74) Attorney, Agent, or Firm — Fross, Zelnick, Lehrman & Zissu, P.C.; Alexandra E. Kochian(57) CLAIM

The ornamental design for footwear, as shown and described.

DESCRIPTION

FIG. 1 is a front perspective view of footwear showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the footwear that form no part of the claimed design.
